HUMIDOR FOR CIGAR AND TOBACCO CASES

John P. Mohen, Clayton, Mo.

Application April 19, 1947, Serial No. 742,641

1 Claim. (Cl. 299—20)

1
This invention relates to humidors for cigar and tobacco cases, as designed for keeping the contents of the case properly moist and in good condition at all times.

The principal object of the invention is to provide a moistener of this kind which comprises certain practical improvements in respect of its structural features whereby it is rendered more compact and attractive in appearance and more efficient in use.

Another object of the invention is to provide a moistener of the kind referred to, the same comprising a base tray for catching drip water, a water seal within the bottom of the tray for protecting same against corrosion, an open topped and impervious water receptacle preferably of glass positioned within the tray upon the water seal thereof, the said tray being of somewhat greater diameter than the water receptacle and so that the upturned flanges of the tray stand spaced outwardly from the sides of the water receptacle, so as to catch the drip water or moisture running down the sides of the water receptacle, a hollow funnel-like water absorbent and humidifying vessel removably seated atop the impervious water receptacle, this vessel being closed at its top, sides and bottom except for a small filler vent through the top thereof and a pendant and hollow stem of similar absorbent material and preferably formed integrally with the said humidifying vessel, projected downward into the water receptacle through the open top thereof, and means for releasably locking the described elements as a unit.

With the stated objects in view, together with such other and additional objects and advantages as may appear from the specification, attention is directed to the accompanying drawing as exemplifying a preferred embodiment of the invention, and wherein:

Figure 1 is a vertical section through the complete unit or humidor, constructed and assembled as above suggested.

Figure 2 is a top plan view.

Figure 3 is a fragmental side elevation of the lower medial portion of the unit as shown in Figure 1, taken at an angle of ninety degrees to the view of Figure 1. The three views are all on the same scale.

In practising this invention as here exemplified, I provide a circular tray 5 of metal or other suitable material, the same including a bottom portion 5a and upturned side flanges 5b. Within this tray, especially if the same is made of metal, I snugly fit a glass sealing plate 6, and an addi-

tional sealing ring or gasket 7 is mounted within the tray where the plate 6 meets the flanges 5b of the tray 5. Thus a perfect water seal is provided at the bottom of the tray 5. An impervious, 5 open topped water receptacle 8, preferably of glass or other transparent material, and of somewhat smaller diameter than the outer tray 5, is seated within the tray, with the lower peripheral margin of its bottom 8a having a bearing upon the gasket 7 all around the bottom and providing an intermediate air-space 9 between the bottoms of the tray 5 and the water receptacle 8. The upper open end of the receptacle 8 is reduced circumferentially to form an annular indrawn shoulder 8c.

A hollow, funnel-like, capillary and water absorbent vessel 10 is provided and is removably seated atop the open upper end of the receptacle 8, this vessel being closed at its top 10a, except 20 for the filler hole or port 10b, at its sides 10c, and at its bottom 10d except for the pendant hollow spout, stem or tube 10e, preferably formed integrally with the upper body portion of the vessel and of the same absorbent material. The sides 10c of the vessel 10 are extended down below the bottom 10d, to provide an annular pendant flange or skirt 10h which is beveled at its lower and inner margin as shown at 10f, so as to complementally fit down upon the angularly indrawn shoulder 8c of the receptacle 8. From diametrically opposite sides of the pendant flange of skirt 10h, hooked lugs 10g are extended outwardly and may if preferred and as here shown, be formed integrally with the material of the vessel 10. As 25 means for removably securing together the described parts of the humidor, retractile coil springs 11 are provided, the ends thereof being formed as hooks for engaging at their upper ends the rings 12, which rings in turn are seated over the hooked lugs 10g, while the hooks at the lower ends of the springs are inserted under tension through apertures 5c formed through the upper margins of the flange 5b of the tray 5.

As above stated, the vessel 10 is formed of any 30 suitably semi-porous, cibiform and water absorbent material such as plaster of Paris, baked clay, or any other material which is subject to the capillary action of water.

In use, water is filled into the water receptacle 35 8 through the aperture or port 10b in the top of the vessel 10, the water flowing down through the spout, tube or stem 10e into the receptacle 8. Through capillary action the water works up through the walls of the spout 10e into and 40 through the sides 10c of the vessel 10, whence

through evaporation the water is vaporized and is diffused throughout the cigar and tobacco case within which the device is placed, thus suitably moistening the contents of the case. While any desired kind of impervious and opaque material may be used for making the water receptacle 8, glass or some other transparent material is preferred for this purpose for the reason that ornamental rocks, marbles or figures may be placed within this receptacle, thus imparting a very pleasing or ornamental and attractive effect to the entire assembly. Moreover, the amount of water therein is readily seen. The device as described may be readily disassembled for cleaning or other purposes, by merely releasing the fastening springs 11.

While I have here shown and described a specific embodiment of the invention, and specific structural features thereof, these features may be changed and modified as desired, within the scope of the claim.

I claim:

A humidor of the kind described, the same comprising a basal, marginally flanged drip tray, an open topped water receptacle of lesser diameter than the tray seated within the tray, thus providing a marginal drip space between the flanges of the tray and the sides of the water receptacle, a hollow, funnel-like, capillary and water absorbent vessel removably seated atop the open end of the water receptacle, said vessel be-

ing closed at its top except for a small filler port, and closed also at its bottom except for an integrally formed spout of similar capillary material extended down into the water receptacle, the sides of the said capillary water-absorbent vessel being extended down outwardly below its bottom to form a skirt for pendantly surrounding the complementally formed marginal shoulder of the open top of the water receptacle, and means extended vertically between the said pendant skirt of the water-absorbent vessel and the flange of the drip tray for releasably securing the several parts of the device together in a unitary assembly.
